UNITED STATES PATENT OFFICE.

ARTHUR L. GARFORD, OF ELYRIA, OHIO.

BICYCLE SADDLE-POST.

SPECIFICATION forming part of Letters Patent No. 596,699, dated January 4, 1898.

Application filed January 22, 1897. Serial No. 620,300. (No model.)

To all whom it may concern:

Be it known that I, ARTHUR L. GARFORD, a citizen of the United States, residing at Elyria, in the county of Lorain and State of Ohio, have invented certain new and useful Improvements in Bicycle Saddle-Posts; and I do hereby declare the following to be a full, clear, and exact description of the invention, such as will enable others skilled in the art to 5 which it appertains to make and use the same.

The invention relates to improvements in "direct" seat-posts, so called, adapted for securing a bicycle-saddle upon a bicycle.

The object of the invention is to provide a 15 cheap, simple, and easily-operated construction whereby the desired result may be attained.

The invention consists in the construction and combination of parts hereinafter described and claimed.

In the drawings, Figure 1 is a side elevation of my seat-post complete and in use for clamping the spring of a bicycle-saddle. Fig. 2 is a sectional front elevation on line 2 2 of 25 Fig. 1. Fig. 3 is a rear elevation of the post when the clamping-jaws are removed, and Fig. 4 is a detached rear view of said clamping-jaws.

Referring to the parts by letters, A represents the substantially-vertical stem of the 30 post, which is adapted to be secured to the bicycle in the usual manner. Secured to the upper end of this stem in any appropriate manner is a horizontal tube B, which is cut 35 away upon its top side between its ends, thereby forming the substantially-vertical ears b b and a recess b' between them. The seat support or spring G lies in this recess between said ears, resting upon the tube B.

The spring G is held in the position stated by 40 the clamping-jaws C C', which are relatively movable laterally toward and from each other. Both jaws may be movable in the ears b b, as shown in Fig. 2 in the drawings. In such case the said movement may be effected by 45 means of the bolt D, having a threaded end d, which screws into jaw C', a cylindrical shank d', which passes through the jaw C, and a head d², which bears against the jaw C, 50 and causes it to be moved toward the jaw C'.

In the proximate faces of the jaws the 55 grooves c c are cut, which grooves receive and embrace the side edges of the spring G. The top wall of these grooves is beveled substantially as shown, whereby the spring G is

clamped down upon the edges of the tube B as the jaws are drawn nearer to each other.

Modifications of the specific form or arrangement shown in the drawings which are within my invention will readily suggest 60 themselves to one skilled in this art, and I do not wish to be understood as limiting myself to that specific form or arrangement further than the claims require.

Having described my invention, I claim— 65

1. In a direct seat-post, the combination of the stem A, two parallel vertical ears on the upper end thereof, two relatively-movable clamping-jaws supported and surrounded by said ears, and means for moving said jaws 70 relatively toward each other to clamp a saddle-spring placed between said ears, substantially as specified.

2. In a direct seat-post, the combination of the substantially-vertical stem, a horizontal 75 tube secured upon its upper end, which tube is cut away upon its top side between its ends to form two ears and a recess between them which will receive the saddle support or spring, two relatively-movable clamping-jaws 80 having in their proximate faces grooves with beveled top walls, and means for relatively moving said jaws toward each other, substantially as and for the purpose specified.

3. In a direct seat-post, the combination of 85 the stem, and the substantially-horizontal tube on the top of said stem, which tube is cut away on its top side between its ends, thereby forming the ears b b and a recess between them, with two clamping-jaws, mounted 90 in said ears, said jaws having in their inner ends grooves adapted to embrace the edges of the saddle support or spring, and a screw-bolt for moving said clamping-jaws toward each other, substantially as and for the purpose specified. 95

4. The combination, with a bicycle having the seat-post A and a saddle having the supporting-spring G, of the tube B cut away on its upper side and thereby leaving ears b b, 100 the clamping-jaws C and C' having the grooves c c, and means for moving said jaws relatively toward each other and preventing their separation, substantially as described.

In testimony whereof I affix my signature 105 in presence of two witnesses.

ARTHUR L. GARFORD.
